UNITED STATES PATENT OFFICE.

CHARLES AUGUSTUS CARMANY, OF MIDDLETOWN, PENNSYLVANIA.

SUPPORT FOR INCANDESCENT LIGHTS.

SPECIFICATION forming part of Letters Patent No. 544,502, dated August 13, 1895.

Application filed September 8, 1894. Serial No. 522,454. (No model.)

To all whom it may concern:

Be it known that I, CHARLES AUGUSTUS CARMANY, a citizen of the United States, residing at Middletown, in the county of 5 Dauphin and State of Pennsylvania, have invented certain new and useful Improvements in Supports for Incandescent Lights; and I do declare the following to be a full, clear, and exact description of the invention, such as 10 will enable others skilled in the art to which it appertains to make and use the same.

My invention has relation to supports for incandescent electric lights; and it has for its object, among others, to provide a simple and 15 inexpensive support whereby an incandescent electric light may be suspended from a ceiling in any desired position, the adjustment of the light being effected by simply drawing down or pushing upwardly the said 20 light.

A further object is to provide means whereby electric lights of different weights may be suspended from the support and the desired results attained—*i. e.*, the light held in any 25 desired position.

Other objects and advantages of the invention will be apparent from the following description, when taken in connection with the accompanying drawings; and, with the various 30 objects in view, my invention consists in the novel construction, arrangement, and combination of parts, as hereinafter fully described.

In the drawings, Figure 1 is a plan view of 35 my device complete. Figs. 2 and 3 are opposite side elevations, Fig. 2 showing in dotted lines the pawl 41, engaging the notch in the hub of the drum. Fig. 4 is a vertical sectional view. Fig. 5 is a face view of the internal meshing revolving pinion and internally-toothed gear. Fig. 6 is an opposite view thereof. Figs. 7 and 8 are opposite face views of the rotating drum upon which the electric 40 wires or tapes are adapted to wind. Fig. 9 is a face view of the collet or ring to which one end of the main operating-spring is secured. Fig. 10 is a plan view of the block by which the devices are supported from the ceiling. Fig. 11 is a bottom view thereof.

In carrying out my invention I provide a 45 suitable block or support 1, which is constructed of porcelain, lava, or other non-con-

ducting material, and which is adapted to be secured to a ceiling by screws 2 or otherwise. Said block is recessed at opposite sides to receive metallic plates 3, to which the leading-wires of the lamp are adapted to be secured by binding-screws 4, and said plates carry depending screws 5, which are connected by wires 6 with binding-screws 7, carried by 50 spring-plates 8, screwed by screws 9 to the upper face of the block. The plates 8 carry at their inner free ends contact points or pins 10, which project through the block for a purpose presently explained. The upper face of 55 the block is recessed, as at 11, also for a purpose presently apparent.

12 12' indicate suitable standards or supporting-pieces, which are of annular shape and provided with rectangular slots 13, through 70 which are adapted to pass projections 14 on clamping-plates 15, which are provided with slots 16, through which securing-screws 17 pass into the block 1. It will be seen that when the plates 15 are adjusted inwardly to 75 cause their projections 14 to enter the slots of the standards the latter will be firmly held in position, and by loosening the screws 17 and moving the plates 15 outwardly the projections will free the slots and permit the 80 standards to be removed from the block. The supports 12 12' are provided with a series of ears 19, perforated to receive the clamping-bolts 20, presently more fully described. The supports 12 12' are centrally perforated, as at 85 21, and 22 indicates a shaft, one end of which is loosely mounted in the perforation of support 12, while its opposite end is squared, as at 23, and is fitted in a square opening 24 in a collar or bushing 25, which is rotatably 90 mounted in the perforation of the support 12'.

26 indicates a collet or ring which is provided with laterally-projecting pins or lugs 27, adapted to snugly fit within perforations or sockets 28 in the support 12, whereby said 95 ring is held in position against the support. Upon the shaft is fixedly mounted a collar 29, to which one end of a convolute spring 30 is secured, the other end thereof being secured to the ring 26. Thus, by rotating the 100 shaft in the proper direction, the said spring will be wound and its stress increased, while by rotating the said shaft in the opposite direction the stress of said spring will be di-

minished. By fitting a key into the socket of the collar 25 the shaft may be readily turned in either direction, as required. Against the ring 26 is adapted to be fitted a paper, wooden, or other insulating-disk 31, which is provided with perforated ears 32, corresponding in position with the ears 19, and through which pass the bolts 29. The disk 31 is provided with a central opening 33, through which the shaft 22 freely passes.

Secured at one end upon the inside of the collet or ring 26 is a leaf-spring 33, whose opposite end bears upon the outermost convolution of the spring 30, and said bearing-end 15 of the spring 33 is broadened and projects through an opening 34 in the disk 31 and engages with one arm of a lever or pawl 35, which is pivoted upon one of the bolts 20. The opposite end or arm of the pawl lies clear 20 of the path of a pin or lug 36, carried by the winding and unwinding drum 37, which is rotatably mounted upon the shaft. This is the position of the pawl when the parts are 25 in their normal operative positions; but in case the spring 30 should break, then the stress of the same would force the spring 33 toward the inner face of the ring, and this would cause the free end or arm of the pawl to be thrown into the path of the pin or lug 36, and thus prevent the rapid rotation of the drum 37 and consequent descent of the lamp.

The drum 37 is provided with the two outer flanges 38, of metal, and the hub 39, of non-conducting material, said hub being provided 35 in its circumference with a recess or notch 40, into which is adapted to take one end of a pawl 41, of non-conducting material, secured at its opposite end upon a metallic sleeve 42, pivoted upon one of the securing-bolts 20. I 40 would state that the engagement of the pawl with the notch or recess occurs only when the conducting-wires for the lamp have been nearly unwound from the hub, (such engagement being shown in Fig. 2,) the object in view being to prevent the continued rotation 45 of the drum when the said wires are pulled upon and thus prevent breakage or detachment of said wires from the binding-screws.

For securing the conducting-wires to the 50 flanges of the drum I recess the hub, as at 43, and also slot the flanges and loosely insert therein contact-sleeves 44, which lie within the recesses in the hub, and against which sleeves the ends of the conducting-wires are 55 adapted to be clamped by binding-screws 45, which work within the said heads.

46 are spring-arms, secured to the flanges and bearing against the projecting ends of the sleeves 44 to hold the same firmly in place. 60 By pressing the arms 46 outwardly to clear the head of sleeves 44, the latter can be removed and the conducting-wires conveniently and securely fastened in place. The hub of the drum 37 is integral with or has secured 65 to it a gear-wheel 48, which is adapted to mesh with a pinion 49, rotatably mounted

upon a stud 50, carried by a disk 51, loosely mounted upon the collar 25. Said pinion 49 meshes with an internally-toothed wheel or disk 52, which is provided with pins 53, which 70 are adapted to snugly fit within sockets 54 in the support 12', thus holding the disk or wheel 52 incapable of rotation at all times.

In order to increase the tension of the spring when necessary without disturbing the drum 75 or lamp, I secure a ratchet-wheel 55 upon the collar 25, with which ratchet engages a suitable pawl 56, secured on one face of disk 51 and projecting through a slot 57 therein, and held in engagement with the teeth of the 80 ratchet by a spring 58, secured to the opposite face of the disk 51. It will be seen that by fitting a key into the squared socket 24 of the collar 25 the shaft 22 may be turned to effect the winding up of the spring, and at the same 85 time the revolution of the collar 25 causes a rotation of the ratchet-wheel 55, the teeth of which, however, will ride beneath the pawl during such rotation. When the winding is discontinued, the pawl and ratchet again engage, transmitting the increased tension 90 through the disk 51, pinion 49, and pinion 48 to the drum.

The drum when mounted on the shaft makes contact with the lugs or pins 10 through the 95 medium of its flanges 38, and inasmuch as said pins are carried by spring-arms, the contact is maintained at all times during the operation of the device.

The stress of the main spring should be 100 such that the same will about counterbalance the weight of the lamp and maintain the same in any desired position to which it may be adjusted, and so that at the same time said lamp may be either drawn down by gently pulling 105 downwardly upon the same or raised by simply pushing upwardly on the lamp. If it be found that the stress of the spring be not sufficient to accomplish the described results, the shaft may be turned to increase the stress of the 110 spring to the desired extent.

The conducting-wires, which serve to suspend the usual lamp 59 from the device and at the same time conduct the current to the incandescent filament thereof, may be the 115 usual wires employed for this purpose suitably insulated, though I prefer to employ conducting-wires constructed in the form of a flat tape 60, insulated and having a width to adapt it to wind snugly between the flanges 120 of the drum.

In the operation of the device, when the lamp is drawn downwardly the drum 37 will be rotated, and, by reason of the gear-wheel 48 meshing with the pinion 49, the latter will be 125 caused to revolve within the disk 52 and at same time effect the rotation of the disk 51 and the collar 25, whereby the shaft 22 will also be rotated and effect the winding of the spring. When the lamp is to be raised in its 130 position, the same will be assisted in its upward movement by the stress of the previously-

wound spring, the parts moving in the opposite or reverse directions, whereby the spring will be gradually unwound—that is to say, its stress or tension will be decreased.

5 Although I have described my device as being adapted more especially for supporting incandescent electric lights, it will be understood that it may be used for various other purposes, and also for suspending portable 10 telegraph-instruments.

Having thus described my invention, what I claim, and desire to secure by Letters Patent, is—

1. In a device of the character described, the 15 combination with a block, of supports carried thereby and having slots therein, clamping plates having slots, securing screws passing through said slots and into the block, and projections on said plates adapted to enter 20 said slots in the supports, a shaft mounted on said supports, and a drum rotatably mounted on said shaft as and for the purpose specified.

2. In a device of the character described, the 25 combination with a block, of supports carried thereby, spring arms carried by the block, contact pins or lugs carried by the said arms and projecting through the block, a shaft mounted on the supports and a drum rotatably mounted on the shaft and in contact 30 with said pins or studs, as and for the purpose specified.

3. In a device of the character described, the combination with a block, supports carried thereby, a shaft mounted on said supports, a 35 drum rotatably mounted on the shaft and having a hub provided with a notch or recess, a pivoted pawl adapted to engage with said recess, and conducting wires secured to flanges on the drum and upon which wires 40 said pawl is adapted to bear until the said wires have been unwound from the hub, as and for the purpose specified.

4. In a device of the character described, the 45 combination with a block, supports carried thereby, a disk secured to one of said supports, a convolute spring secured at one end to said disk, a shaft to which the opposite end of the spring is secured, a drum rotatably mounted upon the shaft, a leaf spring secured 50 at one end to the disk and bearing at its opposite end upon the convolute spring, a pivoted pawl or lever engaged by said leaf spring, and adapted to be tilted thereby as described, and a drum rotatably mounted upon the shaft 55 and having a pin lying normally out of con-

tact with the said lever and adapted to be struck by the latter when tilted as described.

5. In a device of the character described, the combination with a block, of supports carried thereby, a shaft, a collar loosely mounted upon said shaft, a disk loosely mounted on said collar, an internally toothed gear wheel secured to one of the supports, a drum rotatably mounted upon the shaft, a pinion carried thereby, an intermediate gear wheel loosely 60 carried by the said disk and meshing with the said pinion and internal gear wheel, and a spring operating upon the parts, for the purpose specified.

6. In a device of the character described, the 70 combination with a block, of supports carried thereby, a shaft, a collar loosely mounted upon said shaft, a disk loosely mounted on said collar, an internally toothed gear wheel secured to one of the supports, a drum rotatably mounted upon the shaft, a pinion carried thereby, an intermediate gear wheel loosely 75 carried by the said disk, and meshing with the said pinion, and internal gear wheel, a spring operating upon said parts as described, 80 a ratchet wheel on the collar, and a pawl carried by the disk and engaging said ratchet, as and for the purpose specified.

7. In a device of the character described, the combination with a block, of supports carried 85 thereby, a shaft rotatably mounted at one end in one of said supports, a collar at the opposite end of the shaft rotatably carried by the other support, said collar having a square opening into which a squared end on the 90 shaft fits, a disk secured to one of the supports, a convolute spring secured at one end to said disk and at the opposite end to the shaft, an internally toothed gear wheel secured to the other support, a disk rotatably 95 mounted on said collar, a drum rotatably mounted on the shaft, a pinion carried by said drum, an intermediate gear wheel loosely carried by the said disk and meshing with the said pinion and internal gear wheel, a 100 ratchet wheel on the collar, and a pawl pivoted to the disk carrying the intermediate gear wheel and engaging said ratchet.

In testimony whereof I affix my signature in presence of two witnesses.

CHARLES AUGUSTUS CARMANY.
